Primary Examiner — Marianne Pandozzi*Assistant Examiner* — Jae Liang(74) *Attorney, Agent, or Firm* — Innovation Counsel LLP**CLAIM**

We claim the ornamental design for a flow device, substantially as shown and described.

DESCRIPTION

FIG. 1 is a front left perspective view of a flow device in accordance with the present design;

FIG. 2 is a top left perspective view in open position thereof; FIG. 3 is a bottom left perspective view in open position thereof;

FIG. 4 is a front view thereof;

FIG. 5 is a back view thereof;

FIG. 6 is a right side view thereof;

FIG. 7 is a left side view thereof;

FIG. 8 is a top view thereof; and,

FIG. 9 is a bottom view thereof.

The broken line showing in the figure drawings are included for the purpose of illustration and form no part of the claimed design.
